No. 834,349.

PATENTED OCT. 30, 1906.

G. E. WARREN.
HEEL MAKING MACHINE.
APPLICATION FILED DEC. 13, 1902.

FIG. 1.

UNITED STATES PATENT OFFICE.

GEORGE E. WARREN, OF BOSTON, MASSACHUSETTS, ASSIGNOR
TO UNITED SHOE MACHINERY COMPANY, OF PATERSON, NEW
JERSEY, A CORPORATION OF NEW JERSEY.

HEEL-MAKING MACHINE.

No. 834,349.

Specification of Letters Patent.

Patented Oct. 30, 1906.

Application filed December 13, 1902. Serial No. 135,029.

To all whom it may concern:

Be it known that I, GEORGE E. WARREN, a citizen of the United States, residing at Boston, in the county of Suffolk and State of Massachusetts, have invented certain new and useful Improvements in Heel-Making Machines; and I do hereby declare the following to be a full, clear, and exact description of the invention, such as will enable others skilled in the art to which it appertains to make and use the same.

The present invention relates to heel-making machines, and more particularly to machines for concaving the tops of wooden heels.

In the manufacture of certain classes of wooden heels it is the practice to dispense with the use of a rand for forming a concavity in the upper surface of the heel to fit the heel portion of the sole by scooping out or concaving the top of the heel. The shape of the concavity is generally made to conform more or less accurately to the shape of the last—that is to say, to the shape of the heel of the foot of the wearer of the shoe. Roughly speaking, the concavity should be oblatel spheroidal at the rear and elliptically cylindrical at the front part of the heel.

The object of the present invention is to produce a machine for concaving the tops of heels, whether of wood or leather or other material, and which at one operation will concave the top of the heel to the desired shape without dependence upon the skill or judgment of the operator and with uniformity and speed.

The present invention is especially designed for use in the manufacture of the heel-blocks used in making the heel and counter-protector described in Letters Patent of the United States, No. 706,551, August 12, 1902, granted to William Gordon and myself.

To the above ends the present invention consists in the devices and combinations of devices herein described and more particularly defined in the claims.

The illustrated embodiment of the present invention is constructed as follows, reference

being had to the accompanying drawings, in which—

Figure 1 is a plan of the machine, and Fig. 2 a sectional elevation.

Upon a suitable table or standard (not shown in the drawings) is supported a hollow circular trunk 1. A rotary turret comprising 55 a bearing-ring 2 and a supporting-ring 3, connected by spokes 4, is journaled upon the trunk. In vertical sleeves 5, carried by the turret, are pivoted stems 6, carrying work-holders 7. Each work-holder has shoulders 60 8 and 9 receiving, respectively, the backward and downward thrust of the work and a sliding jaw 10, which engages the upper edge of the heel held in the holder. The jaw 10 is dovetailed to slide vertically in the front 65 of the holder. A screw-pin 11, fixed in the jaw, projects through a vertical slot to the back of the holder, where it is engaged by a slotted hand-lever 12, pivoted at 13. By lowering and raising the hand-lever the jaw 70 may be moved into or out of engagement with the work to hold or release it.

A rotary cutter-head 14 is fixed to a horizontal shaft 15, journaled at 16 16 to a bed-plate 17, adjustably fixed, by means of screws 75 18, passing through slots in the bed-plate, to a plate 19, fixed to the upper end of the trunk 1 by screws 20 and centered thereon by a stem 21. A pulley 22 serves to rotate the shaft and cutter-head by a belt from a source 80 of power.

To bring the work-holders and the work held thereby successively in operative relation with the cutter-head means for slowly and continuously rotating the turret are provided, comprising an annular worm-wheel 23, 85 fixed to the bearing-ring 2 of the turret, and a worm 24, meshing therewith. The worm is rotated by a shaft 25, journaled on the frame or table of the machine and driven by a belt 90 or other connection with a source of power.

As the turret rotates slowly in the direction of the arrow the heels or heel-blocks 26 in the work-holders are successively presented to the cutters of the rapidly-rotating cutter-head. The heel is inserted in the holder

with the upper surface of the heel facing the cutter-head, the breast of the heel being against the shoulder 8. The cutter therefore begins to cut at the rear of the heel and finishes at the breast, and the cutter is arranged to cut downward, so as to hold the heel against the shoulder 9.

In order to flatten the latter part of the curve described by the cutter—*i. e.*, to make the latter part of the concavity substantially elliptically cylindrical—means are provided for slightly turning the work-holders about their stems during the progress of the cut. To the bottom of each stem 6 is attached an arm 27, carrying a cam-roller 28, engaging a cam-path 29 in a cam-ring 31, attached to the plate 19. The greater part of the cam-groove is concentric with the axis of the turret, and the work-holders and their stems are during most of their travel held by the cam-arms in such angular relation with the turret that if they passed the cutter without change of position the cutter would begin to cut at the upper rear edge of the heel and leave at a point in the breast directly over the axis of the stem 6, describing a circular cut between these points; but in order to make the latter part of the cut shallower than it would be under these circumstances an offset 30 is made in the cam-path. This is engaged by the cam-roller 28 after the cutter has traversed about a third of the heel. The offset causes the work to be swung slightly away from the cutter; so that less material is cut out; but the point at which the cutter emerges on the heel will always be the same, owing to the location of the breast over the axis of the stem. In order that the heel may be engaged only by the forward edge of the cutter, its shaft is offset slightly from the center of the machine, as shown.

It is to be noted that the present invention is clearly distinguished from those heel-concaving machines of the prior art in which the concavity conforms to the contour of the cutter, because in the present machine the shape of the concavity depends upon the relative movements of the cutter and work-holder and upon the angle of presentation of the work to the cutter by virtue of which many various shapes of concavity may be produced with one cutter. Again, cutters rotating about an axis parallel to the top of the heel are necessarily large in diameter in order to give the heel approximately the shape of the heel part of the last, whereas by presenting the cutter to the work at an angle, as in the present invention, not only permits the use of a smaller cutter, but secures the further advantage of producing the desired flattening of the central part of the concavity.

I believe I am the first to make a heel-concaving machine in which the relative movements of the work and cutter are on curved lines, a construction which manifestly possesses important advantages over prior machines, in which such motion is rectilinear. 65

The present invention is broad and generic in character and by no means limited to the embodiment illustrated in the accompanying drawings and described herein, as the same may be embodied in other and widely-different forms without departure therefrom. 70

Having thus described the invention, what is claimed is— 75

1. A heel-concaving machine having, in combination, a rotary cutter, a work-support, and means for imparting to the work-support and the cutter a relative motion to cause the cutter to cut transversely of the upper surface of the heel so as to concave said surface, the axis of rotation of the cutter being inclined during the cutting operation to the said surface of the heel but substantially parallel to the plane of motion of the work-support, substantially as described. 80

2. A heel-concaving machine having, in combination, a rotary cutter and means for holding a heel and moving it past the cutter in a direction inclined to but in the same plane with the axis of rotation of the cutter, substantially as described. 90

3. A heel-concaving machine having, in combination, a continuously-rotated routing-cutter, a rotary turret, and a plurality of work-holders carried thereon, the cutter and turret being so positioned that heels held in the holders will come in contact successively with the cutter as the turret is rotated, substantially as described. 95

4. A heel-concaving machine having, in combination, a rotary routing-cutter, a rotary turret carrying work-holders, and means for continuously rotating the turret to bring the upper surfaces of heels held in the work-holders successively into contact with the cutter, substantially as described. 100

5. A heel-concaving machine having, in combination, a cutter, means for holding a heel to be operated upon, means for moving the heel into engagement with and past the cutter, and independent means for varying the depth of the cut during the cutting operation, substantially as described. 110

6. A heel-concaving machine having, in combination, a cutter, a rotatable turret, a work-holder mounted on the turret and rotatable about an axis parallel to the axis of the turret, means for rotating the turret to bring a heel held in the holder into contact with the cutter, and means to turn the holder about its axis on the turret, while the 115

cutter is operating on the heel to vary the depth of the cut, substantially as described.

7. A heel-concaving machine having, in combination, a cutter, a work-support, means for moving the work-support past the cutter, and means for varying the path of movement of the work-support during the time it is passing the cutter, substantially as described.
10. 8. A heel-concaving machine having, in combination, a rotary cutter, a work-support, means for moving the work-support past the cutter in a general direction inclined to the axis of the cutter, and means for varying the path of movement of the work-support during the time it is passing the cutter, substantially as described.

9. A heel-concaving machine having, in combination, a cutter, a work-support, means for moving the work-support past the cutter on a curved path of motion, and means for flattening the curvature of the path of motion of the work-support during the time it is passing the cutter, substantially as described.

10. A heel-concaving machine having, in combination, a rotary cutter engaging the upper surface of the heel, a work-support, and means for positively moving the work-support and cutter relatively to each other to cause the work to be presented to the cutter at such angle and to so vary said angle during the concaving operation that the transverse section of the concavity is flattened at the center and so that the longitudinal section of the concavity is curved at one end and substantially flat at the other, substantially as described.

11. A heel-concaving machine having, in combination, a rotary cutter, a work-support, means for moving the work-support past the cutter to present the work to the

cutter at an angle whereby the section of the cut normal to the plane of motion will be substantially elliptically cylindrical and 45 means for moving the work-support during the cutting operation away from the cutter whereby the section of the cut in the plane of motion will be curved and flattened, substantially as described. 50

12. A heel-concaving machine having, in combination, a rotary cutter, a work-support, primary means for moving the work-support past the cutter on the arc of a circle and secondary means for swinging the work-support as it passes the cutter on a center remote from the primary center of motion, substantially as described. 55

13. A heel-concaving machine having, in combination, a rotary cutter, a work-support, means for revolving the work-support to carry it past the cutter and means for oscillating the work-support as it passes the cutter, substantially as described. 6c

14. A heel-concaving machine, having, in combination, a rotary cutter, a work-support, means for revolving the work-support to bring successive portions of the work in contact with the cutter, and means for oscillating the work-support to vary the contour 70 of the cut, substantially as described. 65

15. A heel-concaving machine, having, in combination, a rotary cutter, a work-support, means for revolving the work-support to carry the work past the cutter, and a cam 75 to impart to the cutter and the work-support a relative separating movement, substantially as described.

In testimony whereof I affix my signature in presence of two witnesses.

GEORGE E. WARREN.
